Application February 12, 1934, Serial No. 710,878

8 Claims.

(Cl. 20—16)

The invention relates primarily to a simple counterbalance for an eccentrically mounted weight, and relates secondarily to a counterbalanced door embodying my new counterbalance.

5 Although there are many uses for the counterbalance, I shall, for the purpose of simplifying the disclosure of my invention, confine the disclosure thereof to a counterbalanced door structure having especial utility as a door for garages or any opening of considerable size. At the present time large doors are either swung on hinges, mounted in horizontal tracks so as to slide between closed and open positions, or mounted so that they may be raised to an overhead position. 10 15 The doors swung on vertical hinges require space into which they may be swung into open position, and where sliding doors are employed, space must be provided for them when they are moved into open position. If a door opening is equipped with a pair of door members adapted to overlap when one of the door members is open, the entire door area cannot be open at one time. Overhead doors, in addition to other disadvantages found in their use, are often difficult to operate. 20 25 My present invention concerns an overhead door which rotates relative to a horizontal axis from lowered to raised position and which may be easily and noiselessly swung from open and closed positions for the reason that it is practically perfectly counterbalanced in all positions. In addition to providing a door which is easily operated and which may be made in a single unit for a door opening of practically any width, the invention is of such simplicity that the cost of manufacture and installation of doors is maintained at a minimum.

30 35 It is an object of the invention to provide for use in doors of the character herein disclosed, and for other purposes, a simple form of counterbalance wherein, by use of springs, the door or other swingably mounted weight may be perfectly counterbalanced in all positions of rotation relative to the axis on which it is swingable.

A further object of the invention is to provide 40 45 a door of the above character which may be easily adjusted to proper closing position after the installation of the parts thereof, and having a simple spring counterbalance means, the effect of which relative to the opening and closing movement of the door may be varied or adjusted to suit requirements or individual preference.

It is a further object of the invention to provide 50 55 a counterbalance means for a weight which is rotatable around an eccentric axis, comprising a force exerting element placed so as to exert a

force along a chordal line extending from a movable point associated with the weight so as to rotate around a center of rotation to a stationary point which is in a position of conjunction with the movable point when the center of gravity of the weight is disposed vertically above the axis of rotation of the weight.

Further objects and advantages of the invention will be brought out in the following part of the specification.

Referring to the drawings, which are for illustrative purposes only,

Fig. 1 is a longitudinally, vertically sectioned view showing an embodiment of the invention employed as a door in a garage, the door being 15 shown in partly raised position.

Fig. 2 is an enlarged fragmentary view showing the door of Fig. 1 in closed position.

Fig. 3 is a longitudinally sectioned view taken as indicated by the line 3—3 of Fig. 2.

Fig. 4 is an enlarged fragmentary sectional view on a plane represented by the line 4—4 of Fig. 3.

Fig. 5 is a fragmentary section on a plane represented by the line 5—5 of Fig. 4.

Fig. 6 is a force-diagram illustrating the operation of the counterbalance means involved in the structure shown in Figs. 1 to 5.

Fig. 7 is a vertically sectioned view showing an alternative form of counterbalance structure involving my invention.

Fig. 8 is a sectional view showing the door of Fig. 7 in raised position.

Fig. 9 is an enlarged perspective detail taken as indicated by the arrow 9 of Fig. 7.

Fig. 10 is a perspective view showing a manner in which a single spring may be connected so as to counterbalance both ends of a door in accordance with my invention.

Fig. 11 is a vertically cross sectioned view showing a form of the invention in which the door is pivotally attached to swingable supporting arms and is guided by means of a link during its movement between raised and lowered positions.

Fig. 12 is a vertically sectioned view showing a form of the invention in which the upper portion of the door is guided so as to travel in a horizontal plane as it is swung between raised and lowered positions.

Fig. 13 is an enlarged fragmentary section on a plane represented by the line 13—13 of Fig. 12.

In Fig. 1 I show a garage 15 having a doorway or door opening 16 of a size to permit passage of a vehicle, such as an automobile 17. For closing the opening 16 a door 18 is provided, this door be- 55

ing shown in open position in Fig. 1 and in closed position in Figs. 2 and 3. The door 18, as shown, is of a size to fill the width of the opening 16 and is of such height that the upper edge 20 thereof 5 nearly reaches the wall edge 21 defining the upper limit of the opening 16. To fill the space 22 between the edges 20 and 21, a cover strip 23 may be secured to the wall edge 21. Projecting across the back of the door on opposite sides of a central 10 horizontal plane are members 24, the ends 25 of which project beyond the sides 26 of the door 18 and extend across the inner faces of the front walls 27 of the garage 15. Secured to the ends of the members 25 are arms 28 which extend perpendicularly to the vertical plane of the door 18 and also horizontally when the door is closed, as 15 shown in Fig. 2.

The arms 28 may be made of light-weight steel channels 31 having inwardly extending lips 32, as 20 shown in Fig. 4. In the rearward end 33 of each channel 31 a slideable block 34 is placed, this block being engaged by a screw 35 which extends through a plate or cap 36 on the rearward extremity of the channel 31. The block 34 has an opening 37 for receiving a pin 38 which projects 25 into a boss 40 formed on a mounting plate 41. As clearly shown in Fig. 3, a mounting plate for the pivot means provided by the pin 38 is mounted adjacent the rearward end 33 of each of the 30 pair of arms 28 and on some stationary part of the garage structure, such as posts or side walls 42 of the garage 15. The arms 28 are of such length that the mounting plates 41 may be placed with their pins 38 spaced from the door opening 35 a distance substantially equal to, but slightly less than, half the height of the door. By operation of the screws 35, the blocks 34 may be adjusted to vary the effective lengths of the arms 28 and thereby easily and quickly adjust the door 18 to a 40 desired position in the opening 16.

Ropes or cables 44 are secured at 45 to the outer portions of the forward ends of the arms 28 and are carried over pulleys 46 mounted above the pivots provided by the pins 38, the distance of 45 each pulley from its corresponding pivot being substantially the same as the distance from the points 45 to the pins 38, the result being that when the door 16 is in closed position, as shown in Fig. 2, the portion 47 of each cable 44 extends at an angle of 45° relative to horizontal or vertical or constitutes a chord of the 90° arc 48 transcribed by the movement of the point 45 between horizontal and vertical positions.

From the pulleys 46 rearward portions 50 of the 55 cables 44 extend to pulling means 51, each of which, as shown in Fig. 2, may consist of a forward attachment plate 52 and a rearward attachment plate 53 with a complement of springs 54 connecting therebetween. The attachment plates 60 52 are connected to the portions 50 of the cables 44, and the attachment plates 53 are secured to a stationary member of the garage. The pulling means 51, acting through the cables 44, exert upward forces for counterbalancing the weight of the door 18 and its attachment so that by lifting 65 on the door when it is in the position shown in Fig. 2, it may be rotated through the dotted line position 55 of Fig. 1 to the raised position in which it is shown in full lines in Fig. 1.

A feature of my invention resides in the use 70 of the counterbalance spring means 51 which exerts its force along a line constituting the chord of the arc 48 of the securement point or points 45 of the upwardly rotatable door structure or other rotatable weight similarly secured, and which 75

spring is so proportioned and positioned that it will exert a zero pull when the point 45 is in the vertical plane A—A of Fig. 2, and exert a pull sufficient to counterbalance the weight of the door and its associated part when the point 45 is in any other position, such as in the lowered position in which it is shown in Fig. 2.

I have discovered a new mathematical relationship which is involved in the counterweight disclosed herein, which will be made clear from a consideration of Fig. 6 in which a weight W rotates on a radius r around a point O. The torque T_w of the weight W around O due to gravity on the weight W swinging about O at the radius r is expressed as follows: 15

$$T_w = Wr \cos x$$

A spring of force constant

$$\frac{W}{r}$$

20

is attached to a stationary point A directly above O a distance r to pull the weight W toward A. The extension of the spring E is zero when r is vertical. The torque T_s around the point O due to the spring is 25

$$T_s = r \cdot \frac{W}{r} E$$

Therefore,

$$r_s = r \cos \frac{1}{2}(90 - x) = r \sqrt{\frac{1 - \cos(90 - x)}{2}} = \sqrt{\frac{1 - \sin x}{2}}$$

$$E_s = r \sin \frac{1}{2}(90 - x)$$

$$E = 2r \sin \frac{1}{2}(90 - x) = 2r \sqrt{\frac{1 - \cos(90 - x)}{2}} = \sqrt{\frac{1 - \sin x}{2}}$$

$$T_s = 2r \frac{W}{r} \sqrt{\frac{(1 - \sin x)(1 - \cos x)}{4}} = Wr \sqrt{1 - \sin^2 x}$$

or

$$T_s = Wr \cos x = T_w$$

Consequently, the system is in equilibrium at all points of a complete revolution of W around O.

In the above manner any weight rotatably mounted, such as the door 18, may be counterbalanced by use of a spring connected so as to exert its force along a chord or path extending from the point 45 to a point above the axis of rotation of the weight. A single spring may be employed, or springs may be placed so as to operate in unison, the number of springs employed varying with the weight of the door. In Figs. 1 to 6 of the drawings I have shown a garage door 18 counterbalanced by separate spring means 51 mounted at opposite ends of the door, each of the spring means substantially counterbalancing half the weight of the door. In the diagrammatic perspective view, Fig. 10, I show the manner in which a door 18' may be counterbalanced by use of a spring 51' through cables 44a and 44b which may be carried over systems of pulleys 55 to connect to the spring 51'. 45

In Figs. 7 and 8 I show an alternative form of my invention in which my new principle of counterbalancing by use of a spring is practically applied without the use of cables or pulleys. In Fig. 7 I show a door opening 16a closed by a door 60 mounted on the forward ends of arms, such as the arm 31' which pivotally engages a supporting member 41'. The arm 31' has bracket plates of triangular form 61 and 62, as shown in Fig. 9, secured to its forward end, providing flanges 63 by which the arm may be secured to members 24 placed across the back of the door 60. plate or bracket 62 has an outer flange 64 extending parallel to the arm 31' and having a series of spring connecting means therealong in the form of holes 65. When the door 60 is swung into raised position, as shown in Fig. 8, the plate or flange 64 assumes a vertical position. From one of the holes 65 in the flange 64 a tension spring 66 is extended to a stationary mounting plate 67 which is secured above and to the right of the flange 64 at approximately an angle of 45°, as shown in Fig. 8, and in such position of conjunction with the flange 64 that the spring 66 will extend between the flange 64 and a flange 68 of the plate 67 in substantially relaxed condition or without being stressed or with very little tension therein. As the door 60 is swung from the raised position of Fig. 8 to the lowered position of Fig. 7, the spring 66 stretches through an angle of substantially 45° or along a chordal line relative to the rotation of the point at which the spring 66 is attached to the arm 31', and counterbalances the half of the door to which it is connected, it being understood that a spring and its necessary attachments are preferably used at each end of the door 60, although a single spring may be used at one end of the door of sufficient strength to counterbalance the entire door.

It will be noted that when the door 60 is in lowered position, the member 64 extends horizontally and at an angle of 90° to the flange 68; therefore, by moving the ends of the spring 66 to different holes in the members 64 and 68, the pull of the spring when the door 60 is in lowered position may be varied. In this form of the invention the ideal conditions disclosed in the form of the invention shown in Fig. 6 are not reached, but the results obtained are entirely practicable, and the equipment necessary for the practice of the invention in this form is very simple and relatively inexpensive. In this alternative form of the invention auxiliary springs 70 may be connected from eyes 71 on the corner of the bracket 62 to plates 73 mounted on the sides of walls 74 in which the opening of the door 16a is formed. When the door is in lowered position, the springs 70 exert upward forces to assist in initial upward movement of the door, and as the door swings into overhead position, as shown in Fig. 8, the springs 70 may be also placed under tension to assist in initiating the closing or lowering movement of the door. For operation of the door, a strap 71' may be suspended from the inner face thereof by which the door may be swung from overhead to lowered position, and a suitable hand grip 72' may be placed on the front face of the door for use in raising the door from the closed position in which it is shown in Fig. 7.

In Fig. 11 I show a door member 75 supported on the outer or leftward end of an arm 76 which is pivotally secured at 77 to a stationary member such as a wall or post. The door member 75 in this form of my invention is not rigidly secured to the end of the arm 76, as in the previous forms of the invention, but is pivotally secured so that it may rotate on a horizontal axis defined by a horizontal pipe 78 which extends laterally from the outer end of the arm 76 which is shown as being equipped with counterweight means consisting of a spring 66a which extends from a plate 64a near the outer end of the arm 76 to a wall plate 67a. From a fitting 80 near the upper edge of the door member 75 a bar or link 81 is extended to a stationary pivot 82 disposed below the pivot point 77 of the arm 76. As the arm

16 swings from the horizontal position in which it is shown in full lines in Fig. 11 to the raised position shown in dotted lines 83, the link 81 swings to a position indicated in dotted lines 84, and the upper end of such link 81 passes rightwardly through an arc 85. In this form of the invention the upper edge of the door does not swing through an arc concentric with the pivot point 77, such as the arc 86, but follows the flatter arc 85, thereby reducing the head room required for the door. During the movement of the door member 75 from lowered position, through an intermediate position such as indicated by the dotted lines 75a, to the raised position thereof indicated by the dotted lines 75b, the door member 75 rotates relative to the outer end of the arm 76, the bracket means 87 by which the door member 75 is secured to the pipe 78 rotating on the pipe 78. In lowered position the door member 75 is substantially perpendicular to the arm 76 but is swung into an acute-angle position relative to the arm 76 as the door 75 and the arm 76 swing upwardly, the door 75 being returned to a perpendicular position relative to the arm 76 when fully raised position of the door is reached.

In Fig. 12 I show a form of the invention in which the head room required for the door is further reduced. In this form of the invention a door member 90 is rotatably secured by means of a bracket 87 to a horizontal pipe 78 mounted on the outer end of an arm 76 having a stationary pivot point 77. Near the upper edge of the door 90 a plate 91, as shown in Fig. 13, is secured, this plate carrying a laterally extending arm 92 having engagement means such as a roller 93 which engages a horizontal slot 94 in a plate 95 adapted to be secured to a vertical wall member 96 parallel to the movement of the roller 93 as the door 90 is swung from lowered position, as shown in full lines in Fig. 12, to the raised position shown in dotted lines 97. As the arm 76 moves upwardly through the dotted line position 98, the roller 93 moves horizontally and rearwardly in the guide means provided by the slot 94, this causing the door 90 to swing through a position indicated by the dotted lines 100 and on the pipe 78 into an angular position relative to the arm 76. When the door reaches its completely raised position indicated by the dotted lines 97, the arm 76, in vertical position indicated by the dotted lines 101, is again in a position perpendicular to the door. In this form of the invention the weight of the door 90 and its associated parts is counterbalanced by a spring 51a, one end of which is connected to a stationary member 53a and the other end of which is connected at 103 to the arm 76 by means of a rope or cable 44a which extends over a sheave 46a mounted vertically above the pivot point 77.

Although I have herein shown and described my invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein but is to be accorded the full scope of the following claims.

I claim as my invention:

1. In combination with a building structure having a wall providing a door opening; a door cooperable with said door opening; an arm extending rearwardly from said door; pivot means at the rear end of said arm on which said arm may swing to carry said door toward a position above

- 5 said pivot means; an attachment means connecting between said door and said arm so as to be swung through an arc as said door is moved around said pivot means; a force exerting element connected to said attachment means and being positioned to exert a force substantially along a chord of said arc; a stationary member connected to said force exerting element, said stationary member being in such position that 10 said force exerting element is substantially relaxed when said door is in a position above said pivot means, said force exerting element being adapted to exert a force to raise said door, the weight on said pivot means progressively increasing as said arm is moved into a position in conjunction with said pivot means; and means for varying the length of said arm so as to adjust said door relative to a desired position in said door opening.
- 15 20. 2. In combination with a building structure having a door opening: a rigid door cooperable with said door opening; a pair of arms extending rearwardly from said door; pivot means at the rear ends of said arms on which said arms may swing to carry said door toward a position above said pivot means; members placed substantially in a vertical plane with said pivot means; force exerting means connected to the forward ends of 15 said arms and being positioned so as to exert a force to swing said arms through an arc as said door is moved around said pivot means, said force exerting means including a spring deformed in proportion to the change in distance between said arms and said members as said arms are moved 20 away from said members by rotation of said door, the weight on said pivot means progressively increasing as said arms are moved into conjunction with said pivot means; and means for varying the lengths of said arms so as to adjust said door relative to a desired position in said door opening.
- 25 30. 3. In combination with a building structure having a wall providing a door opening: a door cooperable with said door opening; a pair of channeled arms extending rearwardly from said door; pivot means at the rear of said arms on which said arms may swing to carry said door toward a position above said pivot means; attachment means connecting between said door and said arms so as to be swung through an arc as said door is moved around said pivot means; force exerting elements connected to said attachment means and being positioned to exert a force substantially along a chord of said arc; stationary members connected to said force exerting elements, said stationary members being in such position that said force exerting elements are substantially relaxed when said door is in a position above said pivot means, said force exerting elements being adapted to exert a force to raise said door, the weight on said pivot means increasing as said arms are moved to a position in conjunction with said pivot means; block members slidably mounted on said arms; and means for adjusting said block members so as to change the pivotal axis of said pivot means relative to said arms.
- 35 40. 4. In combination with a building structure having a wall providing a door opening: a door cooperable with said door opening; a pair of arms extending rearwardly from said door; block members slidably mounted on said arms; pivot means associated with said block members on which said arms may swing to carry said door toward a position above said pivot means; force exerting means connected to the forward ends of said arms and being positioned so as to exert a force to swing said arms through an arc as said door is moved around said pivot means, said force exerting means including a spring deformed in proportion to the change in distance between said arms and said stationary members as said arms are moved away from said members by rotation of said door, the weight on 45 said pivot means progressively increasing as said arms are moved into conjunction with said pivot means; and means associated with said block members for varying the length of said arms so as to adjust said door relative to a desired position in said door opening.
- 45 50. 5. In combination with a building structure having a door opening: a door cooperable with said door opening; a pair of arms extending rearwardly from said door; block members slidably mounted on said arms; pivot means associated with said block members on which said arms may swing to carry said door toward a position above said pivot means; stationary members placed substantially in a vertical plane with said pivot means; force exerting means connected to the forward ends of said arms and being positioned so as to exert a force to swing said arms through an arc as said door is moved around said pivot means, said force exerting means including a spring deformed in proportion to the change in distance between said arms and said stationary members as said arms are moved away from said members by rotation of said door, the weight on 55 said pivot means progressively increasing as said arms are moved into conjunction with said pivot means; and means associated with said block members for varying the length of said arms so as to adjust said door relative to a desired position in said door opening.
- 55 60. 6. A counterbalanced door of the character described, including: a door; an arm extending rearwardly from said door; pivot means at the rear end of said arm on which said arm may swing to carry said door toward a position above 65

of said arms and being positioned so as to exert a force to swing said arms through an arc as said door is moved around said pivot means; and means connected to said block members and adapted for adjustment to change the pivotal axis of said pivot means relative to said arms.

65 70. 5. In combination with a building structure having a wall providing a door opening: a door cooperable with said door opening; a pair of arms extending rearwardly from said door; block members slidably mounted on said arms; pivot means associated with said block members on which said arms may swing to carry said door toward a position above said pivot means; force exerting means connected to the forward ends of said arms and being positioned so as to exert a force to swing said arms through an arc as said door is moved around said pivot means; and screw elements associated with said block members and being adapted for adjustment to change the pivotal axis of said pivot means relative to said arms.

70 75. 6. In combination with a building structure having a door opening: a door cooperable with said door opening; a pair of arms extending rearwardly from said door; block members slidably mounted on said arms; pivot means associated with said block members on which said arms may swing to carry said door toward a position above said pivot means; stationary members placed substantially in a vertical plane with said pivot means; force exerting means connected to the forward ends of said arms and being positioned so as to exert a force to swing said arms through an arc as said door is moved around said pivot means; stationary members placed substantially in a vertical plane with said pivot means; force exerting means connected to the forward ends of said arms and being positioned so as to exert a force to swing said arms through an arc as said door is moved around said pivot means, said force exerting means including a spring deformed in proportion to the change in distance between said arms and said stationary members as said arms are moved away from said members by rotation of said door, the weight on 80 said pivot means progressively increasing as said arms are moved into conjunction with said pivot means; and means associated with said block members for varying the length of said arms so as to adjust said door relative to a desired position in said door opening.

80 85. 7. In combination with a building structure having a door opening: a door cooperable with said door opening; a pair of arms extending rearwardly from said door; block members slidably mounted on said arms; pivot means associated with said block members on which said arms may swing to carry said door toward a position above said pivot means; stationary members placed substantially in a vertical plane with said pivot means; force exerting means connected to the forward ends of said arms and being positioned so as to exert a force to swing said arms through an arc as said door is moved around said pivot means, said force exerting means including a spring deformed in proportion to the change in distance between said arms and said stationary members as said arms are moved away from said members by rotation of said door, the weight on 90 said pivot means progressively increasing as said arms are moved into conjunction with said pivot means; and screws associated with said block members adapted for adjustment to vary the length of said arms so as to centralize said door relative to said door opening.

90 95. 8. A counterbalanced door of the character described, including: a door; an arm extending rearwardly from said door; pivot means at the rear end of said arm on which said arm may swing to carry said door toward a position above 95

5 said pivot means, said arm being pivotally secured to said door; an attachment means connected to said door so as to be swung through an arc as said door is moved around said pivot means; a force exerting element connected to said attachment means and being positioned to exert a force substantially along a chord of said arc; a stationary member connected to said force exerting element, said stationary member being 10 in such position that said force exerting element is substantially relaxed when said door is in a

position above said pivot means, said force exerting element being adapted to exert a force to raise said door, which force varies substantially in proportion to the length of said chord; a link for guiding the door as it moves between relatively closed and open positions; means for pivotally securing one end of said link to said door; and a stationary pivot means attached to the other end of said link. 5

HOWARD B. LEWIS. 10
